(57) **CLAIM**

The ornamental design for a tool for removing laundry from a washer or dryer, as shown and described.

DESCRIPTION

FIG. 1 is a bottom perspective view of a tool for removing laundry from a washer or dryer, showing my new design; FIG. 2 is another bottom perspective view thereof; FIG. 3 is a top perspective view thereof; FIG. 4 is a bottom plan view thereof; FIG. 5 is a top plan view thereof; FIG. 6 is a left-side elevational view thereof, a right-side elevational view being a mirror image thereof; FIG. 7 is a rear elevational view thereof; FIG. 8 is a front elevational view thereof; and, FIG. 9 is a top-front perspective view thereof while in use. The evenly-broken dashed lines in the views illustrate portions of the tool that form no part of the claimed design. The unevenly-broken dash-dot lines in the views define boundaries of the claimed design and form no part of the claimed design. The evenly-broken dashed outline of a human arm and laundry inside of an opened washer in FIG. 9 illustrates environmental matter and forms no part of the claimed design.

1 Claim, 8 Drawing Sheets
